UNITED STATES PATENT OFFICE.

CHARLES L. MOORE, OF DALLAS, TEXAS.

AMUSEMENT DEVICE.

1,226,565.

Specification of Letters Patent. Patented May 15, 1917.

Application filed June 24, 1916. Serial No. 105,653.

To all whom it may concern:

Be it known that I, CHARLES L. MOORE, a citizen of the United States, residing at Dallas, in the county of Dallas and State of 5 Texas, have invented new and useful Improvements in Amusement Devices, of which the following is a specification.

This invention comprehends the provision of an amusement device wherein a weight 10 is adapted to be elevated a distance consistent with the force with which the actuating element is struck, prizes being awarded to those players successful in elevating the weight a predetermined distance.

15 In carrying out the invention I provide means for frictionally engaging the cable for the weight, whereby the friction between these parts can be varied to regulate the speed with which the weight returns to 20 its normal position.

The nature and advantages of the invention will be better understood when the following description is read in connection with the accompanying drawings, the invention 25 residing in the construction, combination and arrangement of parts as claimed.

In the drawings forming part of this specification like numerals of reference indicate similar parts in the several views and 30 wherein:—

Figure 1 is a front elevation of the device.

Fig. 2 is a rear elevation partly in section showing the door in opened position.

35 Fig. 3 is a longitudinal sectional view taken on line 3—3 of Fig. 1.

Fig. 4 is a horizontal sectional view taken on line 4—4 of Fig. 1.

40 Fig. 5 is a similar view taken on line 5—5 of Fig. 1.

Fig. 6 is a detail view of one of the cable grips.

Fig. 7 is a similar view of one of the weights.

45 Referring more particularly to the drawings, in detail A indicates generally a housing or casing which may be constructed from any suitable material and of any desired contour, but is preferably of rectangular

formation in cross section. The housing 50 may be of ornamental design to add to its appearance or attractiveness, while the rear wall 10 has a door opening which is normally closed by means of the door 11, and which latter controls access to the housing. 55

Passed transversely through the housing A is a hollow tubular member 12 which projects a considerable distance beyond the opposite side walls 13 of the housing. Arranged within the member 12 centrally 60 thereof is a bearing 14 for the adjacent extremities of the shafts 15 and 16 respectively, which latter are positioned within the hollow member 12 in axial alinement. The outer ends of the respective shafts project 65 beyond the opposite extremities of the hollow member 12 and have fixed thereon in any suitable manner for rotation with said shafts, actuating elements, which preferably consists of an arm 17 from the opposite 70 ends of which project spherical members or balls 18. It might here be stated that the shafts 15 and 16 are mounted for independent rotation to accommodate right and left hand batters, and operate for a purpose to 75 be hereinafter described.

Carried by each of the shafts 15 and 16 respectively is a spool 19 about which a cable 20 is wound, the latter extending from within the tubular member 12 through an elongated slot 21 and threaded through suitable openings 22 in the horizontal partition 23 disposed within the housing adjacent the top thereof. The extremity of the cable thus depends from the partition 23 within the housing and supports a suitable weight 24. Each weight carries an indicator finger 25 which operates in a vertically disposed slot 26 in the front wall of the housing, the indicator finger being arranged exteriorly thereof and coöperating with suitable indicia arranged along the center of the front wall of the housing to indicate the force of the blow with which the actuating element or arm 17 has been struck. Along the opposite side edges 80 of the front wall are electric lights 27, adapted to be lighted in successive order as the weight is elevated, by suitable contacts 85 28

carried by the weight and adapted to close the circuit of the lights as will be readily understood.

Inclosing the projecting portions of the hollow tubular member 12 are casings 29 which can be of any ornamental design to add to the appearance of the device as a whole, while projecting from each casing is a plurality of clips 30 constituting supports for the bats 31. The latter vary in size and weight to permit the device to be operated by men, women and children.

In practice the actuating element or arm 17 is normally disposed vertically, with the weights 24 resting upon the bottom of the housing A. The player then selects a suitable bat 31 and strikes the lowermost ball 18 with sufficient force to rotate the shaft supporting the arm in a direction to wind the cable 20 thereabout. As above stated the shafts 15 and 16 are independently operable to accommodate right and left hand batters, thus affording the same advantages for both. It is of course understood that a right hand batter will operate the shaft 15 from one side of the housing, while the left hand batters will operate the shaft 16 from the opposite side of the housing. As the cable 20 winds about its respective shaft, the weight 24 carried by the cable will be elevated a distance commensurate with the force of the blow struck. As the weight is elevated the indicator finger 25 operating within the slot 26 coöperates with the indicia on the front wall of the housing to indicate the force of the blow. The indicia on the front wall of the housing is marked at spaced intervals to indicate "first," "second," "third base" and "home plate," and prizes are awarded to those players who successfully elevate the weight to a position along side of the "home plate," which is indicative of a "home run." The electric lights 27 are arranged along side of the different bases and "home plate," and are lighted in successive order as the weight is elevated, and passes each light. The operation of the device thus resembles the playing of the national game of base ball, and has for its object the driving of a "home run" which requires the player to hit a 2,000 pound blow. Arranged within the housing and supported upon the bottom thereof is a register 32 of any conventional form, which is operated by the weight 24 as the latter turns to its normal position, and consequently records the number of times the weight has been displaced.

Secured to the inner side of the front wall of the housing, and arranged above the partition 23 are spaced strips 33, each of which has a longitudinal groove 34 in which the cables 20 are arranged. Swingly mounted upon the partition 23 are turn buckles 35, each of which has pivotally mounted

upon its free extremity a grooved block 36 65 adapted to be disposed in confronting relation to the strips 33 and adjusted relatively thereto by means of the turn buckles to increase or decrease the friction upon the cables 20, with a view of regulating the speed 70 with which the weights 24 gravitate to normal position. The top of the housing is closed by means of a suitable cover or top, whereby all of the operating parts of the device are protected from inclement weather, 75 while the device may be illuminated at night by the electric lights 37 as shown.

While it is believed that from the foregoing description the nature and advantages of the invention will be readily apparent I 80 desire to have it understood that I do not limit myself to the exact construction and arrangement of parts herein illustrated as the same is merely illustrative of the preferred embodiment of the invention, and that 85 such changes may be resorted to when desired as fall within the scope of what is claimed.

What is claimed is:—

1. An amusement device comprising a 90 support, a shaft rotatably mounted thereon, a cable having one end connected with the shaft to be wound thereabout, a weight suspended from the opposite end of the cable, means for rotating the shaft to wind the 95 cable thereon, guides for the cable, a friction clamp for engaging the cable to regulate the descent of the weight, and including a fixed member, a turn buckle pivotally mounted on said support, and a clamping member pivotally associated with said buckle and coöperating with said fixed member to regulate the fall of said weight.

2. An amusement device comprising an elongated vertically disposed housing, laterally disposed extensions projecting from the opposite sides of the housing, a shaft positioned within each of said extensions and mounted for rotation, a right angularly disposed arm carried by the outer end of each shaft, a ball on each end of the shaft, a bat removably supported on said extension with which the ball on one end of the arm is adapted to be struck for rotating said shaft, a cable having one end fixed to the shaft, a 115 weight suspended from the opposite end of the cable and movable within the housing, said weight being adjusted when the cable is wound about the shaft as the latter is rotated, an indicator carried by the weight 120 and disposed exteriorly of the housing and operating in a vertical slot therein, and indicia arranged upon the front wall of the housing with which said indicator coöperates for determining the rise and fall of said weight.

3. An amusement device of the character described comprising a housing, a bearing

arranged therein, a pair of axially aligned shafts journaled in said housing, transversely thereof, the adjacent extremities of said shafts being mounted in said bearing, 5 whereby said shafts are arranged for independent rotation, a cable for each of said shafts, said cable having one end wrapped about its respective shaft, a weight suspend-

ed from the opposite end of the cable, an arm secured to the outer extremity of each 10 shaft, and adapted to be struck manually to rotate the shaft to wind the cable thereabout and elevate said weight.

In testimony whereof I affix my signature.

CHARLES L. MOORE.
